UNITED STATES PATENT OFFICE.

ARTHUR L. COLTON, OF HAMMOND, NEW YORK.

PORTFOLIO SCRAP-BOOK.

SPECIFICATION forming part of Letters Patent No. 251,998, dated January 3, 1882.

Application filed June 13, 1881. (No model.)

To all whom it may concern:

Be it known that I, ARTHUR L. COLTON, of the town of Hammond, county of St. Lawrence, and State of New York, have invented 5 certain new and useful Improvements in Portfolio Scrap-Books, of which the following is a specification.

This invention relates generally to that class of devices which consist of several envelopes 10 contained in inclosing-covers, which envelopes are for the purpose of containing in methodically-arranged and easily-accessible form scraps cut from publications, memoranda on separate sheets, and documents of various kinds, which 15 devices have become known to the trade and to the public under the name of "portfolio scrap-books."

The object of my invention is to produce such 20 a book, the covers of which shall be adapted to remain in substantially parallel relation without reference to the amount of matter inclosed 25 thereby. This object is accomplished by providing the covers and inclosed envelopes with eyelets, through which shall pass a suitable cord or tape, and providing fastenings for said cord, whereby it may be adjustably secured in 30 position, and a greater or less thickness of the book thus provided for.

Referring to the accompanying drawings, 35 which are made a part hereof, and on which similar letters of reference indicate similar parts, Figure 1 is a perspective view of a closed book or portfolio constructed in accordance with my invention; Fig. 2, a transverse section thereof on the dotted line *xx*, showing the string as it passes around and through the parts; Fig. 3, a plan view of the book when open; Fig. 4, a plan view, on an enlarged scale, 40 of the button or belaying-pin, to which the ends of the strings are connected, and the surrounding portion of the cover; and Fig. 5, a detail sectional view of the belaying-pin, showing more clearly than the other views the lateral holes through its shank, and the manner 45 of its attachment to the cover of the book.

In said drawings, the portions marked A B represent the covers to my improved book or portfolio; C, the envelopes therein; D, common eyelets or holes in said covers and said 50 envelopes, through which the cords or tapes

pass; E E', said cords or tapes, and F a button or belaying-pin for fastening them.

The covers A B are preferably simply stiff rectangular pieces of any suitable material, which serve to secure the envelopes C firmly 55 in position, and are alike except that one is provided, in addition to the eyelets, with the button or pin F, while the other is provided with eyelets only.

The envelopes C are preferably of heavy 60 Manila paper, and are most commonly of the size known as "No. 10," (though any size may of course be employed,) and are preferably provided with common eyelets D, as shown in Fig. 3, through which the cords pass.

The eyelets D in the covers and the envelopes are simply plain, common eyelets, and serve their usual purpose of preventing the cords from wearing the holes too rapidly or tearing them out.

The cords E E' are so attached and arranged that the whole device can be easily secured together thereby, with the covers in substantially parallel relation, without reference to the thickness of the contents thereof. The end 75 of the cord E is passed through holes in the hollow shank of the belaying-pin F to the inside thereof, and knotted, as is most plainly shown in Fig. 4. It is then wound around the shank several times, passed across to the other 80 side of the cover A, and down through the eyelets D and all the eyelets in one end of the envelopes and the other cover, carried across to the other end, brought up through the several eyelets, and back to the belaying-pin, 85 where the other end is fastened in like manner as the first. The cord E' is then attached to the center of the cord E, of which it is practically a part, and is brought up the front side of the book, wound around the shank of the 90 belaying-pin, and drawn under itself or under the cord E in the manner shown, which completes the fastening. As the matter in the envelopes accumulates, and the book grows thicker, the parallel relation of the covers is maintained by letting out one or more of the turns in the cord E around the shank of the belaying-pin F, and thus giving more length to said cord.

In fastening the book the user draws upon the cord E', which forces the cord E from a 100

straight line, as indicated by the dotted lines in Fig. 3, and forces the book tightly together, and, when secured in the way shown, maintains it in closed position and proper adjustment.

The belaying-pin F is preferably button-like in form, and hollow. It is provided with two holes through its shank from the outside to the inside, through which the ends of the cord or tape E pass, and in which they are secured. Its head or flange should be of a sufficient size to accommodate several turns of the cord E, so that the book may be adjusted up to a thickness of several inches. As will readily be seen, however, the cords E and E' permit a considerable adjustment without unwinding the turns, and are to that extent independent of the belaying-pin, except as a fastening device.

In using my invention the cord E' is detached from the belaying-pin F and the book opened, when the scrap or document which it is desired to file away is inserted in one of the envelopes. The envelopes are intended to be properly classified and numbered, and arranged with spaces for memoranda of contents, &c., on the back of each. A general index may also be inserted, of the usual form for indexes for blank-books. When the scrap or other matter is properly put away and indexed the book is closed and fastened, as before explained. By this means a very convenient and methodical arrangement of the matters contained in the book may be employed, by means of which any scrap or document may be easily found.

Having thus fully described my said invention, what I claim as new, and desire to secure by Letters Patent, is—

1. The combination, in a portfolio scrap-book, of the covers A and B and envelopes C, all provided with holes or eyelets D, and one of said covers being further provided with a belaying-pin, F, a string, E, passing through said eyelets, both ends of which are attached to the belaying-pin and are adapted to be wound around or unwound from the shank thereof, thus shortening or lengthening the available portion of the string, and a string, E', attached at one end to the string E and free at the other, and adapted to be wound around the belaying-pin, and thus secure the book together, all substantially as set forth.

2. The combination, with the cover B, of the belaying-pin F secured thereto, and provided with lateral holes in its shank, adapted to receive and hold the ends of the string E, and having a head or flange under which the string E' may be wound, and thereby secured, substantially as described, and for the purposes specified.

In witness whereof I have hereunto set my hand and seal, at Indianapolis, Indiana, this 4th day of June, A. D. 1881.

ARTHUR L. COLTON. [L. S.]

In presence of—

C. BRADFORD,
W. H. ELVIN.
